UNITED STATES PATENT OFFICE.

LEO L. PFEIFER, OF COLUMBUS, OHIO, ASSIGNOR TO THE JOHN W. BROWN MANUFACTURING COMPANY, OF COLUMBUS, OHIO, A CORPORATION OF OHIO.

POWER-PRESS.

1,397,779.

Specification of Letters Patent. Patented Nov. 22, 1921.

Application filed June 20, 1919. Serial No. 305,691.

To all whom it may concern:

Be it known that I, LEO L. PFEIFER, a citizen of the United States, residing at Columbus, in the county of Franklin and State 5 of Ohio, have invented certain new and useful Improvements in Power-Presses, of which the following is a specification.

This invention relates broadly to power presses, and has particular reference to the 10 mechanism thereof for controlling their operation, the object of the invention being to provide a hand operated clutch controlling mechanism, which, when used in conjunction with a power press embodying a reciprocating die, will serve to prevent such movements on part of the die as would tend to injure the operator of the press.

Another object of the invention resides in the provision of improved and novel means 20 for controlling the operation of the clutch structure of a power press, said means being of a hand operated character, in order that when the die is being reciprocated, the hands of the operator will be occupied in controlling the operation of said means, and in this manner the hands of the operator will be maintained in positions clear of the path of the traveling die.

With these and other objects in view, as 30 will appear as the description proceeds, the invention accordingly consists in the novel features of construction, combination of elements and arrangement of parts, herein-after to be fully described and to have the 35 scope thereof pointed out in the appended claim.

In the accompanying drawings, forming a part of the present specification, and in which similar characters of reference denote 40 like and corresponding parts:

Figure 1 is a front elevation of a power press equipped with the safety control mechanism comprising the present invention,

Fig. 2 is a side elevation thereof,

Fig. 3 is a fragmentary vertical sectional view taken through the clutch structure of the press,

Fig. 4 is a side elevation of the structure disclosed in Fig. 3,

Fig. 5 is a detail perspective view of the controlling mechanism comprising the present invention, and

Fig. 6 is a detail view of the mechanism for retaining the controlling lever in elevated position.

Referring more particularly to the details of the invention, use is made of a power press 1. This press may be of any desired structure and consists in this instance of a frame 2, which carries the usual horizontal bed 3. Attached to the upper sides of the frame 2 are guides 4, in which are mounted for reciprocation the sides 5 of a die holder 6. In order to effect the reciprocation of the die holder, a crank shaft 7 is rotatably mounted in bearings 8 carried by the upper portion of the frame 2, whereby upon the rotation of the crank shaft, reciprocatory motion will be imparted to the die holder so as to move the latter toward and away from the bed 3.

In order to effect the rotation of the crank shaft, use is made of a clutch structure 9, which is of ordinary construction and is so formed as to permit of but one 75 cycle of operation on the part of the die holder under any given operation. The clutch structure 9, *per se*, does not form the subject matter of the present invention, as other well known devices of equivalent nature may be successfully employed with equal facility in carrying out the aims of the present invention, but inasmuch as the use of the structure 9 disclosed admirably sets forth the operation of the present invention, the following description will be 80 accordingly directed thereto.

Loosely mounted upon the actuating end of the crank shaft 7 is a pulley 10 and in order to connect the latter with the shaft 7 90 for uniform rotation, said shaft is provided with a longitudinally extending key-way, in which is rotatably positioned a substantially semi-circular key 11, the latter being provided with a depending crank arm 12. A 95 coil spring 13 co-operates with the arm 12 and tends to rotate the latter so that the key 11 will lie within the key-way provided in the crank shaft and also in a registering key-way 14 formed in the hub of the pulley 100 10. Obviously, when said key lies within both of said key-ways the pulley 10 and the crank shaft 7 will be splined for simultaneous movement.

However, the tendency on the part of the 105 spring 13 is counteracted by means of a pivoted dog 15, which through the agency of a spring 16, is normally maintained in the path of movement of the arm 12, so that as the latter revolves it will be caused to engage 110

with the dog 15 and retained in such position as to cause the key 11 to remain wholly within the confines of the longitudinal key-way formed in the shaft 7. Thus by lowering 5 the dog 15 so that the same will be clear of the arm 12, said spring 13 may respond to its normal tendency and rotate the key 11, thus enabling the shaft and the pulley to rotate for a single revolution, as it will be manifest that when the dog is released from 10 engagement with the crank arm 12 and the latter has started on its rotational movement, said dog will return to its normal position under the influence exercised by the spring 15 16 and will thus be in position to contact with the arm 12 when the latter completes a full turning movement. It will thus be apparent that the structure 9 provides mechanism whereby the die holder 6 will be caused 20 to complete but one cycle of movement under a given operation, and in this manner serves to minimize injuries to the machine operator by preventing undue movement on part of the die holder.

25 In order to operate the dog 15 so that the same may be released from engagement with the arm 12, prior devices have employed foot controlled means for effecting this purpose. Practice has disclosed, however, that when 30 foot operated devices are utilized in this connection, the operator is inclined to become careless and accidentally press the foot treadle without having his hands clear of the holder 6. In this manner many accidents have occurred on machines attaining a 35 high productive output. Therefore, the present invention contemplates the provision of a control mechanism B which is of such construction as to require both hands of the operator in effecting its successful manipulation. It will thus follow that with both 40 hands occupied in operating the press at positions relatively remote with respect to the die holder 6, accidents will be greatly minimized.

45 In its preferred form the mechanism B comprises a pivoted actuating lever 17, which is pivoted as at 18 upon the frame 2, and the forward end of the lever is provided 50 with a handle 19 which extends through a vertically disposed slot 20 formed in a bracket 21, the latter being rigidly carried upon the forward portions of the frame 2. A link 22 is connected with the lever 17 55 intermediately of its pivot 18 and its handle 19, and the upper end of said link is similarly connected with the stop dog 15, whereby upon the oscillation of the lever 17 simultaneous movement will be imparted to 60 the dog 15, which latter in turn controls the operation of the clutch structure 9. A spring 23 cooperates with the link 22 and tends to force the latter in an upward direction, in order to retain the handle portion 65 of said lever in an elevated position

within the bracket 21 and to assist the spring 16 in holding the dog 15 in engagement with the crank arm 12.

The lever 17 is locked against movement normally by means of a latch 24, the latter being slidably mounted within a longitudinal opening 25 formed in the bracket 21. The spring 26 is also positioned within said opening and normally tends to force the latch 24 into the slot 20 so that the latch will 70 underlie the lever 17 and thus retain the latter in a locked position when elevated. In order to release the lever so that the same may be oscillated, the latch 24 is connected with a rod 27, which latter extends horizontally and is supported for sliding movement within the bracket 21 and within a similar bracket 28, located on the opposite side of the frame 2, said rod terminating in an offset handle portion 29, whereby the same may 75 be grasped to effect release movements on part of the latch 24.

In operation, movement may be imparted to the die holder by grasping the handle portion 29 of the rod 27, with one hand, so that 90 the latch 24 may be retracted from engagement with the lever 17, thus permitting the latter to rock about its fulcrum 18. The handle 19 is grasped with the other hand, and when the latch has been properly retracted, said lever is forced downwardly and its movement in a similar direction is imparted to the dog 15 by reason of the link connection 22. As hereinbefore explained, 95 the release of the dog 15 from engagement with the crank arm 12 permits the power of the pulley 10 to be applied to the crank shaft 7 so that the rotation of the latter may be imparted to the die holder 6, the rotary movement of the crank shaft and the reciprocatory movement of the die holder being compensated for by means of the usual pitman theory. After the movement of the die holder has been initiated, the lever 17 is released so that the same will return to its 100 upward position by virtue of the influence exercised by the spring 23 thereon, this upward movement of the lever also acting to return the dog 15 into the path of movement of the arm 12, thus causing the clutch 105 structure to disconnect the shaft 7 from the pulley 10 after a complete cycle of movement has been effected, this arrest of movement on part of the crank shaft 7, of course, occurs when the die holder is in its elevated 110 position. The lever 17 is automatically locked in its upper position by means of the latch 24, which is provided with a beveled underface 31, whereby when the lever is forced upwardly by the action of its spring, 115 the same will force the latch inwardly until after the lever clears the same, and at this juncture the latch is again forced outwardly by the influence of its spring 26, so that the flat upper surface of the latch will engage 120 125 130

with the under edge of the lever so as to prevent the downward movement on part of the latter.

From the foregoing description, taken in connection with the accompanying drawings, it will be apparent that an attachment of considerable utility has been provided for power presses and similar automatic machinery, said attachment serving to permit of the expeditious operating of a press and reduces to a minimum the element of physical danger heretofore present in effecting their operation. It will be observed that before the die holder can be reciprocated it is necessary for the operator to remove both hands from points contiguous to the holder in order to effect the operation of the control mechanism, and it is this fact essentially that serves to render the present invention successful in carrying out its safeguarding aims. In the event of injury to one or the other of the springs 16 and 23, the remaining spring will still function to maintain related parts in operative positions.

25. What I claim is:

In a power press, a rotatably mounted actuating shaft, a power delivering element capable of rotating independently of said shaft, a manually operated clutch structure

for connecting said shaft and element for rotation in unison, a pivoted stop member co-operative with said clutch structure and normally serving to retain the shaft and power delivering element out of driving relation, a manually operated arm pivoted to the side of the press including a forwardly extending handle, a link between said arm and stop member, a spring co-operative with said link and normally serving to maintain said arm in an elevated position and to retain said stop member in engagement with said clutch structure, a spring pressed latch carried by the front of said press and normally disposed to underlie said arm to prevent oscillation of the latter, said latch including a bevel nose portion and a substantially flat upper surface, and a slidably mounted actuating rod connected with said latch disposed to extend transversely of said press, said rod terminating in a handle portion disposed in spaced relationship from the handle portion of said pivoted arm whereby both hands of the operator will be required in effecting the operation of the clutch operating controlling mechanism. 55

In testimony whereof I affix my signature.

LEO L. PFEIFER.
